FRANK T. JONES, OF BALTIMORE, MARYLAND, ASSIGNOR TO THE JONES SAFETY TRAIN CONTROL SYSTEM COMPANY, OF BALTIMORE, MARYLAND, A CORPORATION OF MARYLAND.

BRAKE-VALVE-CONTROLLING DEVICE FOR VEHICLES.

1,109,337.

Specification of Letters Patent.

Patented Sept. 1, 1914.

Application filed December 27, 1912. Serial No. 738,783.

To all whom it may concern:

Be it known that I, FRANK T. JONES, a citizen of the United States, residing at Baltimore, in the State of Maryland, have invented certain new and useful Improvements in Brake-Valve-Controlling Devices for Vehicles, of which the following is a specification.

This invention relates to a brake valve controlling device for vehicles and has particular reference to an improved contact shoe and immediately associated devices to be actuated by the shoe engaging or disengaging a ramp rail.

The present invention is designed for use in an automatic train-controlling system such as shown and described in Letters Patent of the United States Number 1,010,371 granted November 28th, 1911 to R. T. and F. T. Jones wherein the roadway is provided at intervals with short or ramp rails with which the contact shoe engages during its passage, by which engagement in case conditions on the road ahead are safe, a temporary or substitute current is picked up to momentarily maintain the valve controlling apparatus on the vehicle in a normal safe condition while the normal circuit on the vehicle is interrupted by the movement imparted to the shoe by the said ramp rails.

The invention is illustrated in the accompanying drawing, wherein,

Figure 1, shows a side elevation of a portion of a vehicle truck on which the improved shoe and switch devices are carried and also shows a portion of the roadway; a ramp rail and the circuits, and Fig. 2, illustrates the shoe proper and an end of a ramp rail in plan view.

Referring to the drawing by numerals, 1, designates the truck frame of the vehicle; 2, the axle, and, 3, one of the wheels. Supports, 4, are carried by the frame and sustain a horizontal bracket, 5, on top of which a switch box, 6, is rigidly secured. The construction and operation of the switch mechanism in the box, 6, will hereinafter be explained.

A bracket plate, 7, is rigidly sustained beneath the bracket, 5, and said plate has two spaced-apart downwardly extending arms, 8. To the arms, 8, the shoe, 9, is pivotally connected. This shoe has substantially a U-shape, being provided with the spaced-

apart side bars, 10, and a cross-bar, 11, which connects the side bars. The cross-bar, 11, serves as the current collector in that it extends crosswise of the ramp rails over which it passes and completes a substitute circuit only during its contact with the ramp rails and then only in case the road ahead is clear. The ends, 12, of the side bars of the shoe are pivotally connected with the spaced-apart arms, 8, of the bracket-plate, 7, by means of bolts, 13, and to avoid the necessity of drawing these bolts tight to maintain an electrical connection between at least one end of said ends and the arms, 8, I have formed a shoulder, 14, on the bolts so that the bars, 10, may be rigidly secured on the bolts against said shoulder by means of a nut, 15, and I permit the larger portion of the bolt to extend freely through the arm, 8. A spring, 16, is then interposed between the rigid head on one of the bolts and one arm, 8, so that an electrical connection may be maintained from the arm, 8, through the spring to the bolt and from the latter to the bar, 10. In practice, the cross-bar, 11, of the shoe trails at the rear of the depending arms, 8, so that in Fig. 1 of the drawing the shoe is shown as leaving the ramp rail, 16. It will thus be understood that the cross-bar, 11, is located at the free-end of the shoe because it is that end which is raised and lowered upon passing onto and from the ramp rail. The free end of the shoe is therefore utilized to actuate a switch mechanism as will now be described.

A link rod, 17, has its lower end pivotally attached to the free end of the shoe by means of a bolt, 18, and a spring, 19, on the bolt serves as an additional means to insure an electrical connection between the shoe and the rod by seating the clip part of the rod against the shoe. The upper end of the link rod, 17, extends above the bracket, 5, and is secured in a coupling head, 20, which latter normally rests on a plate, 21, on the upper side of the bracket. A spring, 22, is coiled around the link rod, 17, and is sufficiently compressed normally to keep the rod and free end of the shoe depressed.

A shaft, 23, extends horizontally in the switch box, 6, and one end of this shaft extends through an opening in the side wall of the box so that one end of a crank arm, 24,

may be attached thereto. The other end of said crank arm extends toward and is pivotally connected to the head, 20, on the upper end of the link rod, 17, so that when the shoe 5 is moved vertically the shaft, 23, will be given a partial rotation. On the interior of the switch box the shaft, 23, carries a switch arm, 25, whose free end is provided with a block of insulation, 26, to prevent the passage 10 of a current therethrough. A binding post, 27, and a contact block, 28, are also provided in the switch box, 6, and the post, 27, is provided with a switch plate, 29, which carries a roller, 30, so that the latter will lie 15 in the path of the insulation block, 26, on the switch arm, 25. The switch plate has a free end, 31, which normally makes contact with the block, 28, by reason of the fact that under normal running condition and while 20 the shoe is in the lowered position the arm, 25, presses the roller, 30, and switch plate, 29, in a direction toward the contact block, 28, so that the free end, 31, of said plate makes contact with the said block, 28, and 25 closes a circuit between post, 27, and block, 28. A bond or wire, 32, extends from the post, 27, down to one of the arms, 8, of the bracket plate, 7, so as to electrically connect 30 said post and bracket plate.

The purpose of the post, 27, contact, 28, and switch plate, 29, are to maintain a circuit on the vehicle while the latter is traveling from one ramp rail to another along the road and by means of this circuit to hold 35 an air-brake valve normally in an inoperated condition. The mechanism for effecting this is in the present instance precisely the same as that disclosed in said Patent 1,010,371, hereinbefore referred to and consists of a valve device, 33, interposed in a 40 pipe of the air-brake system so as not to interfere with the ordinary manipulations of the air-brake system, said valve having a weighted arm, 34, and a trip-arm, 35. The trip-arm is normally engaged by an armature, 36, of an electro-magnet, 37, and said 45 armature is maintained in position to hold the trip arm so long as the electro-magnet is kept energized.

A battery, 38, is provided on the vehicle 50 and the circuit for normally energizing the electro-magnet is as follows: from battery, 38, by wire, 39, to electro-magnet, 37, then by wire, 40, to shaft, 23, in the switch box, 55 6; then crank, 24, head, 20, link rod, 17, and shoe, 9, to arms, 8; then by bond or wire, 32, to post, 27, switch plate 29, and block, 28, and finally by wire, 41, back to battery. It will thus be seen that as long as switch- 60 plate, 29, is pushed by arm, 25, to close the circuit between post, 27, and block, 28, the circuit from battery, 38, on the vehicle to the electro-magnet, 37, and return will be completed and under such conditions the 65 air-brake valve will be held in the inoper-

ated position. It will also be seen that by including the shoe in this normal circuit in such a way that the current must pass from one end of the shoe to the other to normally prevent the deenergization of vehicle magnet, 37, the shoe must be in operative condition or the normal circuit would be interrupted. Therefore if the shoe should break, the normal circuit would be interrupted causing an application of the brakes. 75

By referring to Fig. 2, of the drawing it will be seen that during the travel of the vehicle the shoe will be presented to the successive ramp rails in such a way that the two downwardly-extending arms, 8, which depend from the bracket, 5, will straddle the ramp rails, 16, and the trailing cross-bar, 11, of the shoe will wipe over the top surface of said ramp rail and will be moved because of the inclined surfaces, 42, which are provided at each end of every ramp rail. This upward movement of the shoe upon passing onto a ramp rail will cause bar, 17, and the free end of crank, 24, to also rise, and shaft, 23, will be turned so as to swing the free end of switch-arm, 25, downwardly, thereby removing the forward pressure on the roller, 30, and allowing switch plate, 29, to spring rearwardly, as shown in broken lines in Fig. 1, so as to break contact with block, 28, and thus interrupt the normal vehicle circuit between battery, 38, and electro-magnet, 37. In this manner the electro-magnet, 37, would be deenergized and the air-brake valve, 33, released so as to vent the train line and effect an application of the brakes, provided some other circuit is not in the meantime substituted through the said electro-magnet. 90

The system with which the present invention is designed to coöperate provides a substitute circuit for the electro-magnet, 37, on the vehicle while the shoe is traveling over a ramp rail in case the track ahead is clear but fails to supply this substitute circuit if the track ahead is occupied or a dangerous condition is present somewhere ahead. This substitute circuit, during periods of safety is provided from a track or roadway battery, 43, from one side of which 105 a wire, 44, leads to and connects ramp rail, 16. A wire 45, leads from the other side of the track battery, 43, and connects with an armature, 46, of an electro-magnet, 47. As long as this armature, 46, is attracted by the electro-magnet, 47, it will 110 be held in contact with a plate, 48, which latter is connected by a wire, 49, with one of the rails, 50, on which the vehicle wheels, 3, travel. Energization of 115 electro-magnet, 47, is effected by a current through a line wire, 51, which is supplied from a block ahead, in case the latter is clear, as explained in said U. S. Patent 1,010,371 hereinbefore referred to. 120

From the foregoing explanation it will be understood that when the shoe, 9, on the vehicle passes up the inclined end of a ramp rail it not only breaks the normal vehicle circuit from vehicle battery, 38, through vehicle magnet, 37, but if the track ahead is clear it simultaneously completes a substitute circuit from track battery, 43, by wire, 44, ramp rail, 16, bar, 11, link bar, 17, head, 20, crank, 24, to shaft, 23, in the switch box; then by wire, 40, to vehicle magnet, 37, to substitute the track-battery current and keep said vehicle magnet energized so as to prevent air-brake valve, 33, from actuating. The return of this substitute current is effected by wire, 39, to wire, 52, which latter leads to the axle, 2; then through wheel, 3, to track rail, 50, and from the track rail by wire, 49, contact, 48, armature, 46, and wire, 45, back to the track battery, 43. This substitute circuit is only maintained while the shoe is passing over the ramp rail and is broken as the shoe lowers when leaving the inclined surface, 42, at the opposite end of the ramp rail, whereupon the normal vehicle circuit will be reestablished.

Obviously if a dangerous condition exists in the track ahead and track magnet, 47, is deenergized, the current from the track battery, 43, cannot pass from wire, 45, to contact, 48, because armature, 46, will have dropped from the contact, 48, consequently the ramp rail will be electrically disconnected from track battery, 43, and cannot supply the substitute current to the vehicle magnet, 37, and the latter will become deenergized and allow the air-brake valve to operate to set the brakes.

Having thus described my invention what I claim and desire to secure by Letters Patent is:—

1. A contact shoe for engaging ramp rails

in safety appliances for vehicles comprising two spaced-apart side bars to extend in vertical planes along the opposite sides of a ramp rail with means for pivotally sustaining said bars at one end and said shoe having a cross-bar connecting said spaced side bars whereby said cross-bar may engage the contact surface of the ramp rails and be moved vertically thereby.

2. In a train controlling valve device for vehicles the combination with a controlling valve on the vehicle, of electrically-controlled means on the vehicle for normally holding the valve in one position; a contact shoe engaging ramp rails along the road,—said shoe comprising two spaced-apart side bars to extend in vertical planes along opposite sides of the ramp rail said shoe being pivoted at one end and having a cross-bar extending crosswise of and connecting said spaced side bars whereby said cross-bar will extend crosswise of the ramp rail to engage the contact surface of said rail and be moved vertically thereby; means for electrically connecting the free cross-bar end of the shoe with one side of the electrically-controlled means that holds the valve and means for connecting the pivoted end of at least one side bar of the shoe with the other side of the said electrically-controlled means one of said electric connections including a battery whereby a normal circuit will be formed through the electrically-controlled means said circuit including the pivoted and the free ends of the shoe while the shoe is traveling between ramp rails.

In testimony whereof I affix my signature in presence of two witnesses.

FRANK T. JONES.
